US0D1060705S

(12) **United States Design Patent** (10) **Patent No.:** **US D1,060,705 S**
(45) **Date of Patent:** **** Feb. 4, 2025**

(54) **PERCUSSION MASSAGER**

- (71) Applicant: **MerchSource, LLC**, Irvine, CA (US)
(72) Inventors: **Rene Jon Hart**, New Canaan, CT (US);
David Yang, Santa Ana, CA (US);
Mark Filipek, Mission Viejo, CA (US)
(73) Assignee: **MerchSource, LLC**, Irvine, CA (US)
(**) Term: **15 Years**
(21) Appl. No.: **29/895,574**
(22) Filed: **Jun. 22, 2023**

Related U.S. Application Data

(57) **CLAIM**

The ornamental design for a percussion massager, as shown and described.

DESCRIPTION

FIG. 1 is a top, perspective view of the front and left side of the percussion massager of the present design.

FIG. 2 is a bottom, perspective view of rear and right side of the percussion massager of FIG. 1.

FIG. 3 is a side elevation view of the left side of the percussion massager of FIG. 1.

FIG. 4 is a side elevation view of the right side of the percussion massager of FIG. 1.

FIG. 5 is a front elevation view of the percussion massager of FIG. 1.

FIG. 6 is a rear elevation view of the percussion massager of FIG. 1.

FIG. 7 is a top plan view of the percussion massager of FIG. 1; and,

FIG. 8 is a bottom plan view of the percussion massager of FIG. 1.

In the drawings, the broken lines depict portions of the percussion massager that form no part of the claimed design.

1 Claim, 6 Drawing Sheets
